US00D593844S

(12) **United States Design Patent**
Petzl

(10) **Patent No.:** **US D593,844 S**
(45) **Date of Patent:** **** Jun. 9, 2009**

(54) **CLIMBING APPARATUS**

(75) Inventor: **Paul Petzl**, Barraux (FR)

(73) Assignee: **Zedel**, Crolles (FR)

(**) Term: **14 Years**

(21) Appl. No.: **29/310,000**

(22) Filed: **Dec. 2, 2008**

(30) **Foreign Application Priority Data**

Jun. 5, 2008 (EM) 000953054-0001

(51) **LOC (9) Cl.** **08-05**

(52) **U.S. Cl.** **D8/356**

(58) **Field of Classification Search** D8/105,

(57) **CLAIM**

The ornamental design for a climbing apparatus, as shown and described.

DESCRIPTION

FIG. 1 is a perspective view of a climbing apparatus;

FIG. 2 is a front view thereof, the rear view being a mirror image;

FIG. 3 is a left-side view thereof;

FIG. 4 is a right-side view thereof;

FIG. 5 is a top view thereof; and,

FIG. 6 is a bottom view thereof.

The broken lines depict environmental subject matter only and form no part of the claimed design.
